UNITED STATES PATENT OFFICE

EVANGELOS L. CARATHANASIS, OF DETROIT, MICHIGAN

VAPORIZER FOR INTERNAL-COMBUSTION ENGINES

Application filed October 18, 1924, Serial No. 743,316, and in Canada June 9, 1924.

My invention relates to improvements in fuel feed systems for internal combustion engines and has for its object the provision of a novel and highly efficient vaporizer 5 adapted to be installed in the fuel feed line leading from the carburetor to the combustion chambers whereby the fuel will be thoroughly mixed and completely vaporized before entering the combustion chambers.

10 This application is a continuation in part of my application Serial No. 532,114, filed January 27, 1922.

An object of my invention is the employment in a vaporizer of the character described of a cup-shaped baffle member over which the fuel flows before entering the combustion chambers, which baffle member is heated by the exhaust from the engine being led thereover and is adapted to collect such 20 condensations of fuel as may occur in the intake and to retain the same within the influence of the heat of the exhaust to be thereby vaporized and is provided with an outlet through which the cup may be drained of 25 material collected therein which is difficult of volatilization.

A feature of importance is the construction of the vaporizer of a minimum number of easily assembled parts and provided with 30 a baffle cup as above set forth, which cup is jacketed for the passage of exhaust gases therethrough and provided with an exterior corrugated surface over which the fuel passes in flowing through the intake. The vaporizer is so formed that swirls are produced in 35 the mixture before it strikes the apex of the outer surface of the cup and this agitation is continued after the fuel passes over the heated surface of the cup by internal fins 40 within the vaporizer.

The above objects and others, together with details of construction, will more fully appear from the following description of the preferred embodiment of my invention illustrated in the accompanying drawings and defined in the claims.

In the drawings.—

Figure 1 is a side elevation of an internal combustion engine provided with my invention.

Fig. 2 is a cross-sectional view through my vaporizer taken on line 2—2, Fig. 1.

Fig. 3 is a vertical sectional view taken on line 3—3, Fig. 2.

Fig. 4 is a horizontal sectional view taken on line 4—4, Fig. 2.

Fig. 5 is a horizontal sectional view taken on line 5—5, Figs. 2 and 3.

Fig. 6 is a side elevation of my vaporizer taken at right angles to the view in Fig. 1.

Let 10 indicate my internal combustion engine having an intake 12, an exhaust 14 and a carburetor 16. My vaporizer is shown in assembly in Fig. 1 as 18 and comprises an outer casing having a lower portion 20 shaped as shown in Figs. 2 and 3, and provided with an inlet portion 22 of reduced diameter which communicates with the outlet from the carburetor. This inlet portion is provided with internal slightly spiral fins 24, one of which is shown in Fig. 3. These fins tend to set up swirls in the gas passing therethrough. The upper portion of the casing indicated as 26 is shown as formed integrally with the intake manifold 12. This casing portion 26 is provided with internal vertical ribs 28 and the outer wall is provided with fins 30 to increase the radiating surface.

Disposed within the interior of the enlarged lower casing member 20 is an outwardly corrugated jacketed cup-shaped baffle member 32, which baffle member 32 is spaced from the wall of the casing 20 so as to permit fuel to flow over the outer surface of the baffle and over the upper edge 36 of the cup to enter the portion of the chamber bounded by the annular casting 38 which annular member is provided with spiral ribs 40 formed on its inner surface. The outer surface of the cup-shaped member is provided with vertically extending fins 34.

I have shown the cup-shaped member 32 and the ring casting 38 as integrally formed, the cup being supported from the ring by the U-shaped tube 42. The cup is really an enlarged tubular jacketed portion formed in the tube 42 and the inner wall of the cup is shaped as shown in Fig. 4 at 44 to provide an enlarged passageway for exhaust gas,

though it will appear from Figs. 2, 3 and 4 the exhaust gas entering the jacketed portion of the cup may flow over the entire inner surface to heat the walls of the cup.

5 The three sections of the vaporizer may be secured together by suitable screws 46 in the manner shown in Fig. 2. The ends of the tubes 42 are adapted to be secured to tapered branches 48 leading from the exhaust manifold and back to the exhaust manifold so that 10 exhaust gas is taken from the exhaust manifold and passed through the interior of the cup and discharged back into the exhaust manifold thereby heating the cup.

15 The fuel mixture flowing from the carburetor to the combustion chambers swirls upwardly over the apex of the cup and along its vertically corrugated outer wall which is heated by the exhaust gases passing through 20 the jacket of the cup and is substantially completely volatilized. The fuel mixture flows over the edge of the cup and the agitation thereof is continued by the fins 40 to swirl the mixture up into the crown member 25 26. This crown portion 26 is provided with external fins 30 to increase its radiating surface and cool the wall thereof and the inner surface is provided with fins 28 to present the maximum surface thereof to the passing 30 mixture.

The cup is so disposed that it will collect all the fuel which may be condensed in the intake above the mouth of the cup. The condensation will gather in the interior of the cup 35 and the volatile portions will be carried off in the form of a gas. Those portions of the mixture incapable of volatilization under the heat conditions present may be drained from the cup through the discharge outlet 50 which 40 extends downwardly through the intake as shown in Figs. 2 and 3, and is provided at the lower end with a removable plug 52.

With the use of a vaporizer of the type here shown a steady, even flow of a thoroughly mixed and volatilized fuel is fed to the combustion chambers and the utmost efficiency of the internal combustion engine is assured with a substantial increase in mileage and smooth and even operation. Moreover, any 45 condensation of fuel which may occur in the intake gathers in the cup and is subjected to the heat of the exhaust gases passing through the jacket and all those portions capable of combustion in the engine are volatilized and drawn into the combustion chambers and such amount of heavy residuum incapable under the conditions present of being volatilized may be drained from the cup 50 through the outlet 52.

60 What I claim is:

1. A vaporizer for an internal combustion engine provided with an inlet and an outlet for the fuel mixture passing from the carburetor to the combustion chambers, and provided with an outwardly corrugated jacketed

baffle cup positioned therein so the fuel mixture will flow over the outer surface thereof, the jacketed wall of said cup provided with an inlet and outlet for exhaust gases, and a drain pipe extending from the bottom of said cup 70 to discharge externally of the vaporizer.

2. A vaporizer for an internal combustion engine having a fuel intake and an exhaust, comprising a conduit leading from the exhaust through the intake and provided with 75 an enlargement in the form of a jacketed cup-shaped structure depending within the intake spaced from the wall thereof to baffle the flow of fuel therethrough and to collect condensation of fuel therein.

3. A vaporizer for an internal combustion engine having a fuel intake and an exhaust for products of combustion, comprising a passageway for exhaust gases leading from the exhaust through the intake and provided with an enlargement in the form of a jacketed cup-shaped structure depending within the intake spaced from the wall thereof to baffle the flow of fuel through the intake and adapted to collect condensation of fuel 85 within the intake above the cup-shaped structure, said intake constricted above said cup-shaped structure and provided about its constricted portion with external radiating fins.

4. A vaporizer for an internal combustion engine having an inlet and an outlet for the fuel mixture passing from the carburetor to the combustion chambers and provided with a jacketed baffle cup positioned therein above the inlet and below the outlet to collect condensation forming within the vaporizer above the cup, said vaporizer shaped above the cup to form a dome thereover having internal ribs arranged to set up swirls in the gas mixture passing therethrough, said cup having 100 external fins and provided with an outlet extending through the wall of the vaporizer, means for conducting exhaust gas from the engine to said jacketed baffle cup, said cup 105 provided with an outlet for said exhaust gas. 110

5. A vaporizer for an internal combustion engine having an inlet and an outlet for the fuel mixture (passing from the carburetor to the combustion chambers) comprising a cup-shaped bottom portion with the inlet disposed at the bottom thereof, a dome-shaped top portion with the outlet positioned at the top thereof and an annular portion secured in place between the top and bottom portions and provided with a jacketed cup-shaped baffle depending within the bottom portion spaced from the wall thereof, said baffle cup provided with an inlet and an outlet for exhaust gases, means connecting the inlet with the engine to receive exhaust gas therefrom. 115

6. A fuel vaporizer comprising, in combination, a hollow upright lower cup-shaped portion having an inlet at its lower end, an annular portion between said upper and lower 120 130

cup-shaped portions and secured to the upper end of said lower portion as an extension thereof, said three portions forming a hollow container having an inlet at the bottom 5 and an outlet at the top, and a second hollow upright cup-shaped portion positioned within the first mentioned upright hollow cup-shaped portion spaced from the wall thereof so that fuel entering through the inlet flows 10 over the outer wall of the second cup-shaped portion toward the outlet, and a conduit for heated gas extending through the intermediate portion and over the inner wall of the second cup-shaped member being exposed 15 thereto.

7. A vaporizer for an internal combustion engine having an inlet and an outlet for the fuel mixture passing from the carburetor to the combustion chambers and provided with 20 an upright jacketed baffle cup positioned therein above the inlet and below the outlet and spaced from the wall thereof providing an annular fuel passageway therein about the wall of the cup whereby fuel entering through 25 the inlet flows upwardly through said passageway over the wall of the cup toward the outlet, said cup being adapted to catch condensation forming within the vaporizer above the open end of the cup, means for conveying a heating medium from the engine to 30 the jacketed wall of the cup, said cup provided with an outlet for said heating medium.

8. A vaporizer for an internal combustion engine having an inlet and an outlet for the 35 fuel mixture passing from the carburetor to the combustion chambers and provided with a jacketed outwardly corrugated baffle cup positioned upright therein below the outlet and spaced from the wall forming an annular fuel passageway around said cup, said 40 vaporizer having a dome-shaped portion disposed above said cup and over which the fuel passes to discharge through the outlet, said cup being adapted to catch condensation 45 forming upon said dome-shaped portion above the open end of the cup, means for conveying a heating medium from the engine to the jacketed wall of the cup, said cup provided with an outlet for said heating medium. 50

9. A vaporizer for an internal combustion engine provided with an inlet and an outlet for the fuel mixture passing from the carburetor to the combustion chambers and provided with a baffle cup positioned upright therein below the outlet and spaced from the wall of the vaporizer forming an annular fuel passageway therein about the cup whereby 55 the fuel mixture entering through the inlet flows through said passageway over the wall of the cup toward the outlet, said cup adapted to catch condensation forming within the vaporizer above the open mouth thereof and 60 means for heating the cup, a conduit com-

municating with the engine for conveying a heating medium therefrom and including said jacketed cup as a part thereof.

In testimony whereof, I sign this specification.
